FOLDING STEPS

Grosvenor D. Marcy, Newton, Mass.

Application September 7, 1955, Serial No. 37,835

Term of patent 14 years

(Cl. D15—8)

Fig. 1.

Fig. 2.

Fig. 3.

Fig. 1 of the drawings is a view in perspective, showing folding steps embodying my new design.

Fig. 2 is a view illustrating the steps in folded position, and

Fig. 3 is a fragmentary elevational view of the bottom step illustrating the arcuate configuration of the brace element.

My design for folding steps is characterized by the wide top platform step in association with the elongated rear supports, which supports are capped by cylindrical hand grips.

I claim:

The ornamental design for folding steps, substantially as shown and described.
